(57) **CLAIM**

The ornamental design for a sprayer for dishwasher, as
shown and described.

DESCRIPTION

FIG. 1 is a perspective view for a sprayer for dishwasher showing our new design, which is illustrated in an exemplary location in a dishwasher;

FIG. 2 is an enlarged perspective view of a sprayer for dishwasher;

FIG. 3 is a front view thereof, the rear view being a mirror image thereof;

FIG. 4 is a right side view thereof, the left side being a mirror image thereof; and,

FIG. 5 is a top view thereof.

The solid line circles in the claim illustrate holes. The areas inside the solid line circles are not part of the claimed design. The broken line holes on the article illustrate boundaries of the claim and are not part of the claimed design. The additional broken lines in FIG. 1 illustrate environment and form no part of the claimed design.
